UNITED STATES PATENT OFFICE

172,907

MOBILE POWER GENERATING UNIT

Norman I. Schafler, New York, N. Y., assignor to
Consolidated Diesel Electric Corporation, Stamford, Conn., a corporation of New York

Application August 11, 1953, Serial No. 26,413

Term of patent 14 years

(Cl. D14—3)

To all whom it may concern:

Be it known that I, Norman I. Schafler, a citizen of the United States, residing at New York, in the county of New York and State of New York, have invented a new, original, and ornamental Design for a Mobile Power Generating Unit, of which the following is a specification, reference being had to the accompanying drawings, forming part thereof.

In the drawings:

Fig. 1 is a right side elevation view of a mobile power generating unit, showing my new design;

Fig. 2 is a front elevational view on a reduced scale of that shown in Fig. 1;

Fig. 3 is a rear elevational view on a reduced scale of that shown in Fig. 1;

Fig. 4 is a fragmentary left side view of the rear portion thereof on a reduced scale of that shown in Fig. 1; and

Fig. 5 is a top plan view on an enlarged scale of that shown in Fig. 1.

I claim:

The ornamental design for a mobile power generating unit, substantially as shown.
